UNITED STATES PATENT OFFICE.

JOHN KIRK FARRIS, OF SENTINEL, OKLAHOMA.

ROAD SCRAPER.

Application filed July 23, 1926. Serial No. 124,514.

This invention relates to road scrapers and more particularly to a device including a bucket for removing earth from projecting portions of the road and transporting the same to depressions in the road, where they may be dumped.

An important object of the invention is to provide a device of this character which may be operated by pushing the same either with a tractor or team and in which the various controls may be readily manipulated without the necessity of the operator diverting his attention from the work being done.

A further object of the invention is to provide a novel leverage connection between the bucket and the means for pushing the same constantly urging the bucket to tilt and discharge its contents, there being a latch preventing the tilting of the bucket until released by the operator.

A further object of the invention is to provide means for limiting movement of the bucket when it arrives at a vertical or discharging position, together with means for regulating the distance between the lip or cutting edge of the bucket when the bucket is in this position, which is adjustable so that the depth of the layer of dirt deposited by the bucket, may be regulated.

A further object of the invention is to provide a device of this character which may be readily and cheaply constructed, which will be durable and efficient in service and a general improvement in the art.

These and other objects I attain by the construction shown in the accompanying drawings, wherein for the purpose of illustration is shown a preferred embodiment of my invention and wherein:

Figure 1 is a side elevation showing a road scraper constructed in accordance with my invention attached to a tractor to be operated thereby, the scraper being shown in the dirt loading position;

Figure 2 is a side elevation of the scraper showing the same in the dumping position;

Figure 3 is a plan view of the scraper;

Figure 4 is a sectional view on the line 4—4 of Figure 1;

Figure 5 is a section on the line 5—5 of Figure 1.

Referring now more particularly to the drawings, the bucket proper is of the usual construction including a bottom plate 10, from the side and rear edges of which walls 11 and 12 project upwardly. In accordance

with my invention, upon the side walls 11 adjacent the top thereof, I mount socket bearings 13 in a manner permitting their adjustment longitudinally of the wall from front to back thereof. These bearings receive spherical heads 14 on the ends of the arms 15 of a U-shaped bail 16. The cross bar 17 of this bail connects with a pair of rearwardly extending pusher arms 18 which overlie the inturned ends 15a of the arms 15 of the U, so that these arms always incline upwardly and forwardly from the pivots thereof.

To the side walls 11 adjacent the bottoms thereof, I secure other sockets 19, openings being provided at 20 for adjusting the sockets longitudinally of the side wall. In these sockets are engaged the spherical heads 21 at the ends of the arms 22 of a second U-shaped bail 23, which projects rearwardly from the pivots thereof. Links 24, which are adjustable as to length, as at 25, are connected at their lower ends at 26 to the bail 23 and at their upper ends at 27 to the pusher arms 18 at points spaced from the forward ends thereof. Ball and socket joints are provided at each point 26 and 27. To the cross bar 28 of the bail 23, a rigid arm 29 is secured having associated therewith a latch 30 which, in the horizontal position of the bucket, hooks over the upper edge of the rear wall 12. This latch is connected with the arm 29 by a spring 31, so that upon a pull on the chain 32 secured to the latch, it disengages from the wall 12.

To the side walls 11 adjacent the lower ends thereof and at the forward ends of these walls, I secure at 33 forwardly extending braces 34, the forward ends of which each engage one end of a shoe 35, the opposite end of which is adjustably connected with the side wall at 36, so that the projection of the face 37 of this shoe beyond the forward edge of the bucket bottom may be adjustably regulated. When the bucket is vertically disposed, it rests upon the faces 37 of the shoes 35 and accordingly by adjusting the shoe 35, the depth of the layer of dirt left, when the bucket is dumped and pushed forwardly over the pile thus formed, may be regulated.

In loading the bucket, the latch 30 is engaged over the upper end of the rear wall and accordingly prevents oscillation of the bucket. When, however, the latch is released, the friction upon the bottom of the

bucket will tend to check the motion of the bucket. Since the pull upon the bucket is from the rear ends of the arms 15 of the U-shaped bail 16 and these arms incline upwardly and forwardly, the push applied by the arms 18 will tend to elevate the rear end of the bucket, so that it finally comes to rest upon the shoe 37. At this time, motion of the bucket is checked, by reason of the fact that the bail 23 engages against the bottom of the bucket. This bail likewise serves, by its rotation about the pivots 19, to swing the latch 30 and arm 29 during the dumping operation to positions where they do not interfere in any way with the movement of the bucket. In order to assist in transportation, the U-shaped yoke 38 has the ends of the arms 39 thereof pivoted to the sides 11 of the body at 40. These arms are provided with shoes 41, which, when the upper end of the yoke is drawn rearwardly through the control chains 42, engage with the ground and elevate the bottom of the bucket from the ground. When the device is employed with a tractor, the push arms 18 are preferably connected at their rear ends by a cross bar 43 which forms a pivot for the arms since it is pivotally engaged with the hitch 44 at the rear of the tractor. In order to relieve the strain upon the ends of the cross bar, these ends may be connected by flexible elements 45 with the tractor frame at any suitable point, as indicated at 46. Adjacent the forward end of the tractor, the arms are directed through guides 47 secured to the tractor frame and having vertically elongated eyes 48 through which the arms pass. These eyes permit vertical movements of the arms, such as are necessary to the dumping operation, but prevent any transverse movement thereof.

Since the construction hereinbefore set forth is capable of a certain range of change and modification without materially departing from the spirit of the invention, I do not limit myself to such specific structure except as hereinafter claimed.

I claim:—

1. In combination with a scoop bucket having the usual side and rear walls and bottom, a U-shaped bail having the ends of the arms thereof pivoted to the side walls at a point adjacent the upper ends thereof and at the rear of said side walls and projecting forwardly from said pivots, pusher arms pivoted to opposite ends of the cross bar of the bail and extending rearwardly over the arms of the bail, and a latch normally preventing vertical movement of the rear end of the bucket with relation to the pusher arms.

2. In combination with a scoop bucket having the usual side and rear walls and bottom, a U-shaped bail having the ends of the arms thereof pivoted to the side walls

at a point adjacent the upper ends thereof and at the rear of said side walls and projecting forwardly from said pivots, pusher arms pivoted to opposite ends of the cross bar of the bail and extending rearwardly over the arms of the bail, a latch normally preventing vertical movement of the rear end of the bucket with relation to the pusher arms and a mounting for said latch having connection with said pusher arms whereby it engages against the bottom of the bucket during a dumping operation to limit rotation of the bucket when the bottom of the bucket is at a predetermined angle to the ground. 75

3. In combination with a scoop bucket having the usual side and rear walls and bottom, a U-shaped bail having the ends of the arms thereof pivoted to the side walls at a point adjacent the upper ends thereof and at the rear of said side walls and projecting forwardly from said pivots, pusher arms pivoted to opposite ends of the cross bar of the bail and extending rearwardly over the arms of the bail, a latch normally preventing vertical movement of the rear end of the bucket with relation to the pusher arms, a mounting for said latch having connection with said pusher arms whereby it engages against the bottom of the bucket during a dumping operation to limit rotation of the bucket when the bottom of the bucket is at a predetermined angle to the ground and shoes secured to the forward ends of the side walls of the bucket and engaging the ground during a dumping operation to maintain the forward edge of the bottom of the bucket in spaced relation to the ground. 90

4. In combination with a scoop bucket having the usual side and rear walls and bottom, a U-shaped bail having the ends of the arms thereof pivoted to the side walls at a point adjacent the upper ends thereof and at the rear of said side walls and projecting forwardly from said pivots, pusher arms pivoted to opposite ends of the cross bar of the bail and extending rearwardly over the arms of the bail, a latch normally preventing vertical movement of the rear end of the bucket with relation to the pusher arms, a second U-shaped bail having the ends of the arms thereof pivoted to the side walls adjacent the bottoms of the side walls and extending rearwardly from its pivots and links connecting said pusher arms and the last named bail and maintaining the cross arm of the bail in substantially fixed spaced relation to the pusher arms. 105

5. In combination with a scoop bucket having the usual side and rear walls and bottom, a U-shaped bail having the ends of the arms thereof pivoted to the side walls at a point adjacent the upper ends thereof and at the rear of said side walls and project- 125

- ing forwardly from said pivots, pusher arms pivoted to opposite ends of the cross bar of the bail and extending rearwardly over the arms of the bail, a latch normally preventing vertical movement of the rear end of the bucket with relation to the pusher arms, a second U-shaped bail having the ends of the arms thereof pivoted to the side walls adjacent the bottoms of the side walls and extending rearwardly from its pivots and links connecting said pusher arms and the last named bail and maintaining the cross arm of the bail in substantially fixed spaced relation to the pusher arms, the cross bar of the last named bail engaging the bottom of the bucket during a dumping operation to limit rotation of the bucket when the bottom of the bucket is at a predetermined angle to the ground.

6. In combination with a scoop bucket having the usual side and rear walls and bottom a U-shaped bail having the ends of the arms thereof pivoted to the side walls at a point adjacent the upper ends thereof and at the rear of said side walls and projecting forwardly from said pivots, pusher arms pivoted to opposite ends of the cross bar of the bail and extending rearwardly over the arms of the bail, a latch normally preventing vertical movement of the rear end of the bucket with relation to the pusher arms, a second U-shaped bail having the ends of the arms thereof pivoted to the side walls adjacent the bottoms of the side walls and extending rearwardly from its pivots, links connecting said pusher arms and the last named bail and maintaining the cross arm of the bail in substantially fixed spaced relation to the pusher arms, the cross bar of the last named bail engaging the bottom of the bucket during a dumping operation to limit rotation of the bucket when the bottom of the bucket is at a predetermined angle to the ground, the cross bar of the last named bail having a rigid arm and a spring connecting said latch and said arm and normally positioning the latch for engagement with the upper end of the rear wall of the bucket when the bucket is in loading position.

In testimony whereof I hereunto affix my signature.

JOHN KIRK FARRIS.

In testimony whereof I hereunto affix my signature.
